(57) **CLAIM**

The ornamental design for a roll-aboard travel bag, as shown and described.

DESCRIPTION

FIG. 1 is a top front isometric view of a roll-aboard travel bag with the trolley handle retracted.

FIG. 2 is a bottom rear isometric view of the roll-aboard travel bag.

FIG. 3 is a left view of the roll-aboard travel bag.

FIG. 4 is a front view of the roll-aboard travel bag.

FIG. 5 is a side view of the roll-aboard travel bag.

FIG. 6 is a rear view of the roll-aboard travel bag.

FIG. 7 is a top view of the roll-aboard travel bag.

FIG. 8 is a bottom view of the roll-aboard travel bag.

FIG. 9 is a top front isometric view of a roll-aboard travel bag with the trolley handle partially extended.

FIG. 10 is an enlarged partial top front isometric view showing the lower corner of the roll-aboard travel bag.

FIG. 11 is a top front isometric view of a roll-aboard travel bag with the trolley handle retracted.

FIG. 12 is a left view of the roll-aboard travel bag.

FIG. 13 is a front view of the roll-aboard travel bag.

FIG. 14 is a side view of the roll-aboard travel bag.

FIG. 15 is a rear view of the roll-aboard travel bag.

FIG. 16 is a top view of the roll-aboard travel bag; and,

FIG. 17 is a bottom view of the roll-aboard travel bag.

The evenly broken lines illustrate portions of the roll-aboard travel bag. The unevenly broken lines around the partial view in FIG. 10 illustrate the edge of the enlarged view for convenience of illustration. None of the broken lines form part of the claimed design.
